UNITED STATES PATENT OFFICE

ROY H. McELROY AND PAUL A. MEEHAN, OF DAYTON, OHIO, ASSIGNEES, BY MESNE ASSIGNMENTS, TO HERBERT S. SIMPSON, OF EVANSTON, ILLINOIS

MULLER

Application filed July 23, 1930. Serial No. 470,134.

Our invention relates to mullers.

It is the object of our invention to provide a muller with independent driving heads for the mullers and for the scrapers with independent adjustments, and independently removable as units from a common driving shaft.

It is a further object to provide a muller with a self contained adjustment that is entirely independent of and separate from its driving head, such adjustment being made preferably in the line of the major axis of the muller arm; and it is our object to provide a counterbalanced muller adjustment.

It is a further object to provide a muller pan with a special arrangement of the bottom or wear plates removable in sections according to the degree of wear upon such plates.

It is another object to provide a muller pan which has a heavy supporting guard ring and a lighter side wall.

It is a further object to provide a muller with a resilient tire or mulling surface; and a muller in which the mullers are eccentrically disposed with respect to the driving axis about which they rotate bodily in order to give a kneading effect in the mulling.

It is a further object to provide a self-cleaning, dust-proof, lubricated bearing support for the main driving shaft in conjunction with a one-piece pan bottom and bearing support; and to provide in connection therewith means of maintaining a reservoir of lubricant at a predetermined level around the main bearing of the shaft.

It is another object to provide a special form of dust-proof, adjustable bearing for the muller arm pivot shaft.

It is a further object to provide a novel form of bearing which is self-cleaning for sand and like material for the muller on the end of the muller shaft.

Referring to the drawings:

35 Figure 46 is a detail of the attachment of a scraper to a supporting arm.

Referring to the drawings in detail, 1 indicates the foundation piers upon which there is erected the supporting angle iron framework for the muller pan. This frame work is 40 shown in some detail in Figure 1 and in Figure 10. This frame is composed of a column 2 which is H shape in section. Within the spaces 3 formed by the end members 4 of this column are angle iron braces at the top and bottom designated 5. On the outside there is an angle iron brace 6 at the top and at the bottom. The column 2 and the plate 6 are mounted upon a bottom plate 7 and the column structure carries at its top a top plate 8.

45 Between the columns at the bottom thereof on either side of the structure is a horizontal spacing column designated 9 having attaching reinforcing plates 10 and an intermediate spacing plate 11 for supporting the bearing block 12 that carries the horizontal driving shaft 13 on which is mounted a bevel pinion 14. This pinion 14 meshes with a horizontally disposed bevel gear 15 that is fastened upon the lower end of the main driving shaft 16.

Driving shaft and support

The support of the shaft is shown in detail 65 of Figure 5. This shaft 16 is provided with

a tapered portion 17 at its bottom which expands outwardly and upwardly into the next succeeding cylindrical portion 18 the lower end of which as well as the portion 17 are spaced by the space 19 from the side wall 20 of a bottom closure plate 21 that is attached by the bolts 22 to the underside of the depending hub 23 that is formed integrally with the pan bottom 24 and the upwardly extending bearing support 25, sometimes 75 designated a turret.

This bottom closure plate 21 is formed with a recess 26 for receiving the lower lubricating seal and dust-excluding seal consisting of washers 27, 28 and 29 as well as 80 the base 30 for the reservoir ring 31.

These washers of leather, 27, 28 and 29, are held in metallic cages 32 and are pressed against the shaft 16 by the helical springs 33. The washers 27 and 28 are bent upwardly to resist the outward movement of the lubricant and the washer 29 is bent outwardly to resist the inward movement of the dust and sand through the self-cleaning space 19 which is provided between the surfaces 17, 18 and 20 to permit of foreign material, which may enter, freely dropping out without injuring the shaft 16.

90 The reservoir ring member 30 has a paper washer 34 superimposed between it and the shoulder 35 of the hub 23. The reservoir ring 31 extends upwardly to the point 36 above the bottom 37 of the lubricant reservoir formed by the bottom 37 and side 100 walls 38 of the bearing receiving chamber 39. 36 being located at the point above 37, a sufficient quantity of lubricant is always stored around the tapered roller bearing 40 which supports the shaft 16 through engagement of the shaft 41 with that plate which is the lower side of the collar portion 42 on the shaft, the upper side of which supports a tapered bearing 43 between the shaft 16 and the side wall 38 of the chamber 39. The top side bearing is engaged by a spacer sleeve 44 which adjacent its top extends inwardly into the collar 45 with a plurality of horizontally disposed, spaced corrugations 46 which restrict the movement of lubricant by reason of their close association with the shaft 16 and to which they have a slight clearance.

110 Above the spacing sleeve 44 resting upon its upper end 47 is a second tapered roller bearing 48 aligning the shaft laterally. On this bearing rests the adjusting nut 49 threaded at 50 on the upper end of the shaft 16. This adjusting nut is provided with a 115 washer 51 and a lock nut 52 also threaded on the shaft to maintain the adjustment of the nut 49.

120 The top of the bearing support 25 supports the bolts 53 which clamp the dust collar 54 in 130

position with respect to the shaft 16. This collar has a depending aligned flange 55 extending within the turret 25. It is also provided with a plurality of corrugations 56, the edge of which extend closely adjacent to the shaft to prevent entrance of foreign material.

Muller yoke and muller mechanism

- 10 The shaft 16 carries upon shoulder 57 the bottom 58 of the lower muller yoke 59, or muller driving head, which is provided with a depending skirt 60 which encloses the dust collar 54 and the upper end of the turret 25. 15 This yoke 59 is keyed by the key 61 to the shaft 16.

This muller yoke or driving head is provided with oppositely disposed bearing sleeves for the respective muller rocker arm shafts.

The bearing sleeve 62 supports the shaft 63 for the muller 64 which is connected thereto by the rocker arm 65 and the shaft 65a.

25 The bearing sleeve 66 on the other side supports the shaft 67 with similar construction of that of 63 for supporting the rocker arm 68, its shaft 69 and the muller 70. The mullers 64 and 70, the shafts 65a and 69 the rocker arms 65 and 68 and the shafts 63 and 67 are 30 identical in construction.

This lower muller yoke is also provided with an extending arm 71 with a socket 72 for receiving the adjusting screw 73 carried by the scraper yoke 74 hereinafter described.

35 The muller rocker arm shafts 63 and 67 being identical it will be sufficient to describe one of them. The shaft comprises a square head 75 which is inserted within the slotted end 76 in the bearing sleeves 66 or

40 62 as the case may be. That portion of the shaft designated 77 is mounted within the bearing sleeve 66. This bearing sleeve adjacent the other end from the squared end slot 76 is provided with an annular recess

45 78 in which is inserted a bronze collar 79 which is supported by that portion of the shaft 77 which extends outwardly beyond the bearing sleeve 66.

- 50 Supported on this end of the rocker arm shaft 77 is the rocker arm 68 which is bifurcated having spaced arms 80 and 81. The arm 80 is recessed at 82 to receive the bronze collar 79. There is a clearance at 83 left between the bearing collar 66 and the arm 80. It is thus impossible for any sand or any foreign material to work itself down into the surface of the shaft at 77. The arm 80 is provided with a suitable bearing sleeve 84. 55 That portion of the rocker arm shaft extending from arm 80 to 81 is square as at 85 for receiving the adjusting jack arm 86. The extreme end of the shaft carries a bearing sleeve 87 and a nut 88. The sleeve 87 is 60 within the arm 81. There are two bearing

sleeves 80 and 81 on either side of the squared portion of the shaft at 85.

Muller adjustment

A slot 80a between the arms 80 and 81 of the muller rocker arm 68 accommodates the jack arm 86 which is mounted at one end 89 on the square portion 85 of the rocker arm shaft. This arm extends upwardly out of the slot 80a into a head 86a carrying an adjusting screw 86b and a lock nut 86c. The lower end of this screw bears upon a bearing plate 90 that is countersunk in the end 91 of the rocker arm 68. Thus the muller 70 and its shaft 69 may be adjusted in position.

Muller axle support

Turning particularly to Figures 20, it will be noted that the muller axle 69 is retained in a non-rotatable position in the rocker arm 68 by the key 92 and set screw 93. A shoulder 94 on the axle 69 engages one side of the rocker arm 68. The rocker arm is provided with enclosing flanges 95 to enclose and partially guard against foreign material in the connection of the axle 69 with the muller. A guard plate 96 having corrugations 97 adjacent the axle 69 is bolted by the bolts 98 to the inner face of the muller 70 closing one end of the bearing chamber 99 formed within the hub of the muller. Within this bearing chamber are a pair of spaced tapered roller bearings 100 and 101 engaging a shoulder 102 on the shaft and the nut 103 on the shaft respectively. They also engage oppositely disposed shoulders 104 on the inside of the muller 70. The end of this chamber is closed by a plate 105 retained by bolts 106 carried by the muller 70. This end plate is provided with a port 107 closed by a screw plug 108 so that lubricant can be inserted within the bearing chamber 99. It is also provided with a paper washer. The pressure of such lubricant on the outside of the muller serves to drive the grease over the corrugations 97 and thence out of the structure, thus forming a self-cleaning bearing. A hole 109 is provided through which accumulated foreign material is dropped.

Muller construction

The mullers themselves may be of any conventional type. In Figures 21 and 22 we have indicated one typical form of muller. The muller is provided with a hub 70a and a rim 70b having a lagging aperture 70c. The muller is preferably hollow, as at 70d. The rim 110 may be mounted in the lagging apertures and retained thereon by retaining bolts 111 which were inserted both in the rim and the corrugated slots 112 in the rim 70b. This tire 110 is made of rubber and produces a novel result in that the sand is not disintegrated and crushed and its struc-

ture destroyed by mulling which is also objectionable by reason of the amount of dust and fine material which finds its way into the mulling machinery, but the same is thoroughly mixed and yieldingly incorporated with the molasses or other material put into the muller without destroying the integrity of the structure of the grains of sand.

13 *Top yoke for scrapers*

The head for scrapers comprises a collar 113 keyed to the shaft 16 by the key 114. One arm of this head 115 is provided with angularly disposed, vertically arranged slots 116 for receiving a scraper arm, hereinafter described.

On the other side of the head is a second arm 117 carrying a horizontally disposed bearing 118 that pivotally supports this 20 scraper yoke 74 shown in Figures 31, 32 and 33. The yoke 74 is provided with a short arm 119 and a long arm 120 connected by an intermediate bar 121 that carries the adjusting screw 73. The long arm also carries a depending arm 122 that is engaged by the laterally disposed adjusting screw 123 carried on the end of the arm 71 which also receives the vertical adjusting screw 73.

25 The short arm 119 is provided with a semi-circular jaw 123 and a long arm is provided with a similar jaw 124.

The short arm 119 in this jaw 123 receives the strip arm 125 that has an arcuate rear portion 126 seated within the semicircular 25 portion 123. This arm 125 has vertical slots 127 for receiving the bolts 128 to permit a vertical adjustment. The bottom of the scraper arm is provided with a lateral extension 129 and horizontal slots 130 for lateral adjustment of the scraper, shown in Figures 38, 39 and 40, which comprises a vertical plate 131 having transverse ribs 132 and bolt holes 133 through which passes the bolts 134. The 40 lower edge of the scraper is provided with an arcuate scraping portion 135. This same scraper is also mounted upon the arm, shown in Figures 35 and 34, mounted on the long arm 120 of the yoke. The arm in Figures 34 and 35 differs from that shown in Figures 36 and 37 in that its lower end is provided with a laterally disposed plate 129 for supporting the scraper and a rib 129a.

On the other side of the scraper driving head yoke in the groove 116 between the 55 shoulder 116a there is slidably mounted the scraper arm 136 which has a rib 137 and vertical slots 138 for receiving the bolts 139 so as to permit vertical adjustment.

On the bottom of arm 136 are transverse 60 slots 140 for receiving bolts that support the scraper 141 that extends from near the center of the pan to near the periphery thereof. In Figure 46 is shown the three-point contact at points 136a, 136b and 136c between the arm 136 and the scraper 141. This scrap-

er is shown in detail in Figures 28, 29 and 30. It is provided with a relatively deep, vertical portion 142 near the center of the pan and with a relatively shallow portion 143 toward the periphery of the pan.

70

Wear plates

The bottom of the pan which is integral with the corrugated side wall portion forms a heavy rim, designated 144. It is also integral with the turret 25 and pan hub 23. The bottom is provided with door openings 145 and 146 which are closed by suitable doors 147 that are journaled on shafts 148 in eyes 149 on the bottom of the pan 24. These doors have connected to them pitmen 150 pivotally connected to the respective arms 151 and 152 of a bell crank that is pivoted on the side of the pan at 154. This bell crank is provided with a third operating arm 155 that in turn is connected to the piston 156 of an operating air cylinder 157. It will be noted that the bottom of the pan 24 is provided with radial ribs 158, a frame of square ribs 159 and door marginal ribs 160. These ribs are 80 connected to the pads 161 for mounting upon the supporting frame that supports the pan.

80

Within the pan there is mounted a pair of semi-circular wear plates 162 and 163 whose ends 164 abut one another. These wear plates surround the turret and are retained in position by the bolts 165. In addition to these wear plates there are semicircular wear plates 166 and 167 whose ends 168 abut the sides of the door openings. They are likewise held in position by the bolts 169. One-inch diamond-shaped cored holes are formed in the wearing plates, the function of which is to add friction on the base of the pan when fine or slick material is being mulled.

95

100

105

Modified form of muller adjusting mechanism

In Figure 43 we have shown a modification of adjustment of the muller rocker arms. 110 Mounted on the muller driving head or yoke 59 are adjusting screw brackets 170 carrying adjusting screws 171 locked by the lock nut 172. These screws engage with a wear plate 173 on the bottom of the rocker arm carrying each muller, such as 65 or 68.

110

It will be understood that we desire to comprehend within our invention such modifications as may be clearly embraced within the scope of our claims and invention.

120

Having thus fully described our invention, what we claim as new and desire to secure by Letters Patent, is:

1. In a muller, a pan, driving shaft mounted therein, a driving head, mullers pivotally mounted thereon, a second independent head driven by said shaft, scrapers mounted thereon, said scraper head being superimposed over the muller driving head, a swinging yoke on said scraper head carrying one of said

125

130

scrapers, and adjusting means extending from said swinging yoke to the muller head whereby the relationship therebetween may be adjusted.

5 2. In combination in a muller, of a mulling pan, a driving shaft projecting therein, a muller driving head mounted thereon, a rocker arm shaft mounted in said head, a rocker arm pivoted thereon, said shaft being non-
10 rotatable, a muller mounted on the free end of said rocker arm, a jack arm non-rotatably mounted on said rocker arm shaft, and adjusting means between said jack arm and rocker arm for adjusting said muller.

15 3. In combination in a muller, of a mulling pan, a driving shaft projecting therein, a muller driving head mounted thereon, a rocker arm shaft mounted in said head, a rocker arm pivoted thereon, said shaft being non-
20 rotatable, a muller mounted on the free end of said rocker arm, a jack arm non-rotatably mounted on said rocker arm shaft, adjusting means between said jack arm and rocker arm for adjusting said muller, said adjusting
25 means engaging that portion of the rocker arm on the oposite side from the muller with respect to the pivotal support of the rocker arm.

4. In combination in a muller, of a mulling pan, a driving shaft mounted therein, a muller drive head mounted thereon having an arm extending laterally therefrom to one side of the center of said shaft, a rocker arm shaft mounted therein, a rocker arm mounted on
30 said rocker arm shaft, a muller axle mounted in the inner free end of said rocker arm on the opposite side of the drive shaft center from that of the pivotal support of the rocker arm, a muller mounted on said axle so mounted in the free end of the rocker arm and means on the rocker arm shaft for adjusting the muller.

5. In combination in a muller, of a mulling pan, a driving shaft mounted therein, a muller drive head mounted thereon having an arm extending laterally therefrom to one side of the center of said shaft, a rocker arm shaft mounted therein, a rocker arm mounted on
45 said rocker arm shaft, a muller axle mounted in the inner free end of said rocker arm on the opposite side of the drive shaft center from that of the pivotal support of the rocker arm, a muller mounted on said shaft so mounted in the free end of the rocker arm, and adjusting means attached to the rocker arm shaft for adjusting the height of the muller with respect to the pan.

6. In combination in a muller, of a mulling pan, a driving shaft mounted therein, a muller drive head mounted thereon having an arm extending laterally therefrom to one side of the center of said shaft, a rocker arm shaft mounted therein, a rocker arm mounted on
60 said rocker arm shaft, a muller axle mounted in the inner free end of said rocker

arm on the opposite side of the drive shaft center from that of the pivotal support of the rocker arm, a muller mounted on said shaft so mounted in the free end of the rocker arm, and adusting means for adusting the height of the muller with respect to the pan, said means comprising a jack arm on the rocker arm shaft and adjusting means between it and the outer end of the rocker arm on the side of the rocker arm shaft opposite to that on which the muller is mounted.

7. In combination in a muller, of a pan, a concentrically mounted driving shaft, a muller driving head thereon having oppositely-disposed arms, non-rotatable rocker arm shafts mounted in said respective arms parallel to one another on opposite sides of the driving shaft, rocker arms mounted thereon, muller axles mounted in the inner ends of said rocker arms on opposite sides of the center of the driving shaft and on opposite sides of said center with respect to the rocker arm shafts carrying the respective rocker arms, mullers mounted on the muller axles and means on the rocker arm shafts for adjusting the mullers.

8. In combination in a muller, of a pan, a concentrically mounted driving shaft, a muller driving head thereon having oppositely-disposed arms, non-rotatable rocker arm shafts mounted in said respective arms parallel to one another on opposite sides of the driving shaft rocker arms mounted thereon, muller axles mounted in the inner ends of said rocker arms on opposite sides of the center of the driving shaft and on opposite sides of said center with respect to the rocker arms shafts carrying the respective rocker arms, mullers mounted on the muller axles, adjusting means engaging the outer ends of the rocker arms for adjusting the heights of the respective mullers with respect to the pan.

9. In combination in a muller, of a pan, a concentrically mounted driving shaft, a muller driving head thereon having oppositely-disposed arms, non-rotatable rocker arm shafts mounted in said respective arms parallel to one another on opposite sides of the driving shaft rocker arms mounted thereon, muller axles mounted in the inner ends of said rocker arms on opposite sides of the center of the driving shaft and on opposite sides of said center with respect to the rocker arm shafts carrying the respective rocker arms, mullers mounted on the muller axles, adjusting means engaging the outer ends of the rocker arms for adjusting the heights of the respective mullers with respect to the pan, said adjusting means comprising a jack arm mounted on the non-rotatable rocker arm shaft, and an adjusting screw extending from the free end of the arm to the outer end of the rocker arm.

10. In combination in a muller, of a pan, a concentrically mounted driving shaft, a

- 5 muller driving head thereon having oppositely-disposed arms, non-rotatable rocker arm shafts mounted in said respective arms parallel to one another on opposite sides of the driving shaft rocker arms mounted thereon, muller axles mounted in the inner ends of said rocker arms on opposite sides of the center of the driving shaft and on opposite sides of said center with respect to 10 the rocker arm shafts carrying the respective rocker arms, mullers mounted on the muller axles, adjusting means engaging the outer ends of the rocker arms for adjusting the heights of the respective mullers with respect to the pan, a second driving head mounted on said driving shaft having oppositely-disposed arms, a stationary scraper depending from one of said arms, a scraper yoke having depending scrapers pivotally mounted on the 15 other of said arms, and adjusting means between said yoke and the muller driving head for adjusting the relationship therebetween.
11. In combination in a muller, of a pan, 20 a concentrically mounted driving shaft, a muller driving head thereon having oppositely-disposed arms, non-rotatable rocker arm shafts mounted in said respective arms parallel to one another on opposite sides of the driving shaft rocker arms mounted thereon, muller axles mounted in the inner ends of said rocker arms on opposite sides of the center of the driving shaft and on opposite sides of said center with respect to the rocker 25 arm shafts carrying the respective rocker arms, mullers mounted on the muller axles, adjusting means engaging the outer ends of the rocker arms for adjusting the heights of the respective mullers with respect to the pan, a second driving head mounted on said driving shaft having oppositely-disposed arms, a stationary scraper depending from one of said arms, a scraper yoke having depending scrapers pivotally mounted on the other of said arms, adjusting means between said yoke and the muller driving head for adjusting the relationship therebetween, and supplementary means of adjusting the respective scrapers on their supports.
12. In a muller, a muller pan, a vertically-disposed central driving shaft, a lower muller head carrying mullers pivotally mounted thereon, an upper scraper driving head, scrapers mounted thereon, a scraper yoke pivotally mounted on said scraper head carrying a portion of said scrapers, and means of adjusting the position of said yoke with respect to the muller driving head, said adjusting means comprising an arm on the 50 muller driving head and a depending adjusting screw engaging therewith on the muller yoke.
13. In a muller, a muller pan, a vertically-disposed central driving shaft, a lower muller head carrying mullers pivotally mounted thereon, an upper scraper driving head, scrapers mounted thereon, a scraper yoke pivotally mounted on said scraper head carrying a portion of said scrapers, means of adjusting the position of said yoke with respect to the muller driving head, said adjusting means comprising an arm on the muller driving head and a depending adjusting screw engaging therewith on the muller yoke, and adjusting means for said mullers independent of said heads.
14. In a muller, a pan, a central driving shaft, a scraper head mounted thereon, arms on said head, a depending scraper support mounted on one of said arms arranged at an angle to the radius of said pan, and an angularly-disposed scraper extending from said shaft to the periphery of said pan, a second arm on said scraper head, a yoke pivoted thereon having one arm extending to approximately the periphery of the pan and the other to a pan intermediate the driving shaft and the periphery of the pan, segmental scrapers mounted thereon, one of which extends from the periphery of the pan to a point beneath its supporting arm and the other of which extends from the outer supporting arm to a point beyond the inner supporting arm.
15. In a muller, a pan, a central driving shaft, a scraper head mounted thereon, arms on said head, a depending scraper support mounted on one of said arms arranged at an angle to the radius of said pan, and an angularly-disposed scraper extending from said shaft to the periphery of said pan, a second arm on said scraper head, a yoke pivoted thereon having one arm extending to approximately the periphery of the pan and the other to a point intermediate the driving shaft and the periphery of the pan, segmental scrapers mounted thereon, one of which extends from the periphery of the pan to a point beneath its supporting arm and the other of which extends from the outer supporting arm to a point beyond the inner supporting arm, and means carried by said driving shaft for adjustably supporting said yoke.
16. In a muller, a pan, a driving shaft, a scraper head mounted thereon having a laterally extending arm, an angular supporting surface with shoulders on either side thereof on the end of said arm, a slotted plate on said surface between said shoulders and depending therefrom, bolts on said arm mounted in said slots, a scraper mounted on the lower end of said slotted plate, bolts on said scraper extending through transverse slots in the lower end of said arm whereby said arm may be vertically adjusted and the scraper transversely adjusted.
17. In a muller, a pan, a driving shaft, a scraper head mounted thereon having a laterally extending arm, an angular support-

- ing surface with shoulders on either side thereof on the end of said arm, a slotted plate on said surface between said shoulders and depending therefrom, bolts on said arm 5 mounted in said slots, a scraper mounted on the lower end of said slotted arm, bolts on said scraper extending through transverse slots in the lower end of said arm whereby said arm may be vertically adjusted and the 10 scraper transversely adjusted, said scraper having a relatively deep inner flange and an outer shallow flange.
18. In a muller, the combination in a muller adjustment of a muller driving head, a non-rotatable axle mounted therein having a squared portion, a slotted rocker arm mounted on said axle with said squared portion exposed by said slot in the arm, a jack arm mounted on said squared portion between said arms extending to a point over one of the ends of said rocker arm with the slot, an adjusting screw between the free ends of the rocker arm and the jack arm, and a muller pivotally mounted on the other 25 end of said rocker arm.
19. In a muller adjusting mechanism, the combination of a driving shaft, a muller head mounted thereon, a laterally-extending, non-rotatable rocker arm shaft mounted therein having a squared portion, a slotted rocker arm on said rocker arm shaft freely pivoted thereon, a jack arm mounted on said squared portion of the rocker arm shaft in the slot of the rocker arm extending to a 30 point above said rocker arm over one end thereof, adjusting means between the ends of the jack shaft and the rocker arm at one end of the rocker arm, and a muller pivoted on the other end of the rocker arm.
20. In a muller, an integral bottom pan having discharge ports, an integral turret vertically disposed with respect to said pan, and oppositely-disposed, concentric, semi-circular wear plates detachably mounted on said pan, the outer of said plates extending from one side of one port to the other and the inner of said plates extending from the inside of one port to the other.
21. In a muller, a muller pan, a support therefor comprising a pair of spaced legs on either side of said pan, interconnecting means between the bottoms of said legs connecting them in pairs, a driving shaft and a driving shaft bearing mounted on and connecting said interconnecting means to form pillow blocks for said shaft.
22. In a support for a muller pan, a plurality of pairs of H-shaped structural leg members, horizontally-disposed top and bottom plates thereon, angular reinforcing plates on the four sides of the tops and bottoms of said H-shaped structural members, transversely-disposed structural members between the bottoms of each pair or pairs of said legs, reinforcing means therebetween,
- and pillow blocks mounted on said means extending between the legs for supporting a driving shaft.
23. In a support for a muller pan, H-shaped structural members, vertically-disposed top and bottom plates thereon, angular reinforcing plates on the four sides of the top and bottoms of said H-shaped structural members, transversely-disposed structural members between the bottoms of pairs of said legs, reinforcing means therebetween, pillow blocks mounted on said means extending between the legs for supporting a driving shaft, and an integral, one-piece pan bottom mounted on the tops of said legs whereby said bottom and the lower spacing means will maintain said legs in rigid vertical alignment.
24. In a muller, the combination of a muller driving arm having a shaft-receiving aperture, said arm being recessed on one face thereof around said aperture, a rocker arm having an adjacent shaft-receiving opening with a recess therearound, a shaft connecting said driving arm and rocker arm, an annular bearing member mounted on said shaft between said arms in the recess thereof whereby said arms are maintained in spaced engagement on said shaft.
25. In combination, a shaft, a pair of spaced sleeves mounted thereon having annular recesses around said shaft adjacent to one another, and a bearing member mounted on said shaft within said recess maintaining said sleeves in spaced relationship with respect to one another.
- In testimony whereof, we affix our signatures.
